DESIGN FOR AN ILLUMINABLE SIGN LENS

Samuel O. Omohundro, Long Beach, Calif.

Application September 19, 1940, Serial No. 95,215

Term of patent 3½ years

To all whom it may concern:

Be it known that I, Samuel O. Omohundro, a citizen of the United States, residing at Long Beach, in the county of Los Angeles and State of California, have invented a new, original, and ornamental Design for an Illuminable Sign Lens, of which the following is a specification, reference being had to the accompanying drawing, forming part thereof.

In the aforesaid drawing:

Fig. 1 is a side elevational view of an illuminable sign lens showing my new design;

Fig. 2 is a top plan view thereof;

Fig. 3 is a bottom plan view thereof; and

Fig. 4 is a fragmentary sectional view taken on the line 4—4 of Fig. 1.

I claim:

The ornamental design for an illuminable sign lens, as shown.

SAMUEL O. OMOHUNDRO.
